UNITED STATES PATENT OFFICE

GUSTAV A. NAUMANN, OF ST. LOUIS, MISSOURI, ASSIGNOR TO JACOB HUETHER, OF SAME PLACE.

IMPROVEMENT IN JOINERS' CLAMPS.

Specification forming part of Letters Patent No. 179,942, dated July 18, 1876; application filed April 28, 1876.

To all whom it may concern:

Be it known that I, GUSTAV A. NAUMANN, of St. Louis, Missouri, have invented an Improvement in Joiners' Clamps, of which the following is a specification:

This invention is an improvement on patent for joiners' clamp granted to me March 14, 1876, No. 174,838.

As is well known, the two jaws of a joiner's clamp are required to have all the strength possible, so as to be durable for both operation and use. Also, in clamps of this character, in which the movable jaw is rapidly adjustable to any size of hold without the constant working of the hand-screws, it is highly important that the operating parts which lock and unlock the screws should work with dispatch, decision, and reliability, and without possibility of self-disengagement. Lastly, these operating parts should be simple in construction, and easily be made to operate.

Of the drawing, Figure 1 is a sectional side elevation. Fig. 2 is a detail side view of operating parts that lock and unlock the hand-screws. Fig. 3 is a detail perspective, showing construction of the sleeve and its pivoted swinging arm.

A is the stationary jaw; B, its movable or adjustable jaw.

I cast two sleeves, C C', one for the passage of the front and the other for the rear hand-screw. These sleeves have at their one end a flange, c, which limits their insertion into the jaw, as shown in Figs. 1, 2.

The strain of the hand-screws being reversed—viz., the front one acting downward in the movable jaw—I insert the sleeve C from above, the flange c thereof resting on top of the jaw.

The strain of the rear hand-screw being upward in the movable jaw, I insert the sleeve C' from below, and its flange c similarly prevents it from being drawn through the jaw.

I provide the following devices, in connection with the sleeves C C', to lock and unlock the screws, or secure the adjustable jaw in position: D and D' are swinging arms, of the form

shown in Figs. 1 and 3, and having the threads d. These arms are pivoted in slots c', formed or cast in the sleeves C C'.

The arm D is pivoted in the sleeve C at d¹, while the arm D' is pivoted on the sleeve C' at d². The pivoting of the arms gives the advantage that, after they once engage with the screws, the strain bearing on the arms will, of itself, draw them in tighter, and thus make the fastening more secure.

A spring, d³, of sufficient strength, keeps the arms in contact with their respective screws. To take off the strain from the pivots of these arms, a shoulder, d⁴, is cast in these sleeves, upon which the arms rest when the strain is exerted upon them.

To disengage the arms from their respective screws, or, in other words, to allow the movable jaw to be readily adjusted, a slide, E, is provided on top of the movable jaw, of the shape shown in Figs. 1 and 2, and formed with a trigger-shaped stud on top for the operator to take hold of. This slide has at its front end a hook, e, catching the arm D through an eye, d⁵. The other end of the slide has a pin, e¹, engaging into a similar eye, d⁶, in the arm D', and a shoulder, e², pressing against this point of the arm D'.

By drawing this slide E back, its hook e engages the arm D. This arm, being pivoted below, draws said arm back with it and out of engagement with its screw, at the same time compressing its spring. The pin e¹ at the other end of the slide E, engaging the arm D' by means of its shoulder e², pushes this end of the arm along with it; but this latter arm being pivoted above, its lower end is swung forward and out of engagement with its screw, at the same time compressing its spring, and thus the parts stand in the position shown in Fig. 2.

By loosening the slide E the springs return the parts to their original locked position.

As seen in the drawing, but very little of the solid material is cut away from the jaw; also, no screws are required to secure the parts in position; and, from the construction, it will be seen that the improvements here pre-

sented possess the further advantages of cheapness, durability, and effective operation.

What I claim is—

The combination of a swinging arm, D, having threads d , pivoted to a sleeve, C, having slot c' and shoulder d' , in combination with a hand-screw of a joiner's clamp, to operate as set forth.

In testimony of said invention I have hereunto set my hand.

GUSTAV A. NAUMANN.
